WALL-MOUNTED VANITY FOR BEAUTY SALONS

Max G. Peterson, P.O. Box 1992,
Stockton, Calif. 95201

Filed May 3, 1971, Ser. No. 140,003

Term of patent 14 years

Int. Cl. D6—04

U.S. Cl. D6—132

Fig. 1

FIG. 1 is a front elevation of a wall-mounted vanity. FIG. 2 is a side elevation of such wall-mounted vanity. FIG. 3 is an enlarged fragmentary cross section on line 3—3 of FIG. 1.

FIG. 4 is a vertical section on line 4—4 of FIG. 1. FIGS. 5, 6, and 7 are horizontal sections taken on lines 5—5, 6—6, and 7—7, respectively, of FIG. 1.

I claim:

The ornamental design for a wall-mounted vanity for beauty salons, as shown.
